UNITED STATES PATENT OFFICE.

ELIJAH DAWE, OF COLLINGWOOD, CANADA.

SLEEPING-BERTH.

SPECIFICATION forming part of Letters Patent No. 734,519, dated July 28, 1903.

Application filed January 26, 1903. Serial No. 140,645. (No model.)

To all whom it may concern:

Be it known that I, ELIJAH DAWE, tailor, of the town of Collingwood, in the county of Simcoe, in the Province of Ontario, Canada, have 5 invented certain new and useful Improvements in Sleeping-Berths, of which the following is a specification.

My invention relates to improvements in sleeping-berths, more particularly adaptable 10 for railway sleeping-cars and steamship state-rooms; and the object of the invention is to devise a simple means whereby the occupant of the upper berth may readily ascend thereto and be held therein during sleep without 15 any danger of being thrown out; and it consists, essentially, of a stirrup pivotally connected to the end of a bar which is pivoted in the center of the berth, such bar being held up by a spring-catch normally behind the 20 outer side of the berth and a bar pivotally held above the berth on suitable arms when in use, the parts being arranged and constructed in detail as hereinafter more particularly explained.

25 Figure 1 is a perspective view of a portion of a sleeper or state-room, showing an upper and lower berth with portion of the outer side being broken away to exhibit the parts in my invention. Fig. 2 is an enlarged perspective detail showing the inside of the berth. Fig. 3 is a detail of the spring-catch by which the stirrup-bar is normally supported. Fig. 4 is a detail of the spring-catch by which the grasping-bar is normally supported.

35 In the drawings like letters of reference indicate corresponding parts in each figure.

A is the outer side of the berth; B, the stirrup-bar, which is pivoted on a spindle b, which extends through the bearing-bracket 40 b' in the side of the berth and is provided at the outer end with a handle b². The bar B is limited in its throw by the quadrantal guard c, secured to the inside of the berth.

D is the stirrup, which is pivotally secured 45 on the end of the bar B.

E is a spring-catch having a beveled lower side E' and a stem e, which extends through to the front of the berth and is provided with a ring e². A cross-bar e³ is connected to the 50 bar E' and has extending between it and the back of the socket in which it fits spiral springs e⁴, one to each side of the stem e.

The beveled end of the stem extends through a slot e⁴ in the plate E².

In the normal position the stirrup-bar B, as 55 well as the stirrup, is held in position, as shown by full lines in Figs. 1 and 2. In order to throw the stirrup down into position for mounting into the upper berth, the ring e² is pulled outwardly, so as to throw the beveled end E', which has a flat supporting top, inwardly, and thereby allow of the stirrup and bar to assume the position shown in dotted lines in Fig. 1.

F is a bar pivotally supported on the arms 65 f and f'. The end arm f' is provided with a beveled recess f².

G is a catch pivoted in the jaws g of the plate G' and having underneath the outer end the spiral spring g', which is suitably held in 70 position. The opposite end is hooked at g² or practically hooked. It will thus be seen that when the bar F is thrown upwardly by the handle b² into the position shown in dotted lines in the drawings the hooked end 75 of the bar G will pass up the beveled incline of the recess f² and resume the position shown in Fig. 4, the spring g' allowing of the hooked end g² to give sufficiently so as to pass the arm, and such hooked end g² serving 80 to hold the arm, and consequently the bar, in position when the arm is upright. It will now be seen that the person wishing to occupy the upper berth may put his one foot into the stirrup D and grasp the bar F, whereupon he 85 may readily rise and get into such upper berth. When my device is not in use, the stirrup and bar may be pushed up into the position shown in full lines in Figs. 1 and 2, and in passing up it will pass the beveled end of the 90 catch and force it inwardly and pass onwardly to the upper side of it and there remain. By pressing in the spring-supported end of the lever G the hook g is forced outwardly and the arm f' may be thrown downwardly and the bar F restored to the position shown in Figs. 1 and 2.

It will be seen from this description that my device is very simple and will obviate the great inconvenience which has heretofore 100 been experienced in passengers getting up into the upper berths in sleeping-cars and state-rooms.

What I claim as my invention is—

1. In sleeping-berths, the combination with the side of the upper berth, of a bar pivoted at one end of the same and located to the inside of the berth, a stirrup pivotally connected to the opposite end of the bar and designed with the bar to hang downwardly from the side of the berth when in use as and for the purpose specified.

2. In sleeping-berths, the combination with the side of the upper berth, of a bar pivoted at one end of the same and located to the inside of the berth, a stirrup pivotally connected to the opposite end of the bar and designed with the bar to hang downwardly from the side of the berth when in use and a handle on the outer end of the spindle for restoring the bar and stirrup to the closed position as and for the purpose specified.

3. In sleeping-berths, the combination with the side of the upper berth, of a bar pivoted at one end of the same and located to the inside of the berth, a stirrup pivotally connected to the opposite end of the bar and designed with the bar to hang downwardly from the side of the berth when in use and a re- 25 edable spring-catch designed to extend underneath the bar and hold it in a closed position as and for the purpose specified.

4. In sleeping-berths, the combination with the side of the upper berth, of a bar pivoted at one end of the same and located to the inside of the berth, a stirrup pivotally connected to the opposite end of the bar and de-

signed with the bar to hang downwardly from the side of the berth when in use and a catch 35 having a stem extending through the side of the berth, a beveled end, a cross-bar, springs extending behind the cross-bar and a ring at the outer end whereby it may be pulled inwardly, so as to release the bar as and for 40 the purpose specified.

5. In sleeping-berths, the combination with the bar pivoted in the side of the berth and the stirrup pivotally connected to the free end of the bar, of a grasping-bar pivotally 45 connected to arms pivotally connected to the top of the berth, such arms being designed to stand upright, so as to hold the bar above the level of the side of the berth as and for the purpose specified.

6. In sleeping-berths, the combination with the side of the berth, of the arms and bar and means for engaging the arms and holding them upright as and for the purpose specified.

7. In sleeping-berths, the combination with the side of the berth, of the arms and bars, one of the arms being provided with a beveled recess and a spring-actuated lever provided with a hooked end designed to pass through such recess and grip and hold the 55 60 arm when it is in the upright position as and for the purpose specified.

ELIJAH DAWE.
